UNITED STATES PATENT OFFICE.

JOSEPH G. BAIN, OF PITTSBURGH, AND LASZLO M. STEMPLE, OF DORMONT, PENNSYLVANIA, ASSIGNORS TO LEWIS FOUNDRY & MACHINE COMPANY, OF PITTSBURGH, PENNSYLVANIA, A CORPORATION OF PENNSYLVANIA.

BRIDLING APPARATUS.

Application filed April 12, 1922. Serial No. 551,767.

To all whom it may concern:

Be it known that we, JOSEPH G. BAIN and LASZLO M. STEMPLE, both citizens of the United States, residing, respectively, at 5 Pittsburgh, in the county of Allegheny and State of Pennsylvania, and Dormont, in the county of Allegheny and State of Pennsylvania, have invented a new and useful Improvement in a Bridling Apparatus, 10 of which the following is a specification.

This invention relates to a bridling apparatus for use in conjunction with rolling mills.

A general object of the invention is to 15 provide bridling apparatus which is simple and compact, and which avoids the difficult and laborious operation of threading a strip being passed to reducing rolls through stationary bridle bars.

20 A more specific object of the invention is to provide bridling apparatus of the nature noted above which places the strip being rolled under a tension which may be regulated in accordance with the thickness 25 of the strip and the material of which it is composed.

A further specific object of the invention is to provide bridling apparatus which places the strip under a tension sufficient 30 for satisfactory rolling thereof without producing a rubbing of the strip against itself or any other metal.

It is also common practice to roll out 35 metal wires of round or rectangular cross section, and of varying cross sectional area into ribbons. It is desirable that such material, equally with strips be subjected to tension while being passed through the reducing rolls. In the art it is customary to 40 include such forms, as well as the flat forms called strips hereinabove, under the general term of "bars."

A still further object of the invention is, 45 therefore, to provide bridling apparatus embodying the advantages mentioned above which may be arranged or readily adapted for use with bars of round or rectangular cross section as well as with the flat bars more specifically called strips.

50 In the accompanying drawings Figure 1 is a side elevation showing the apparatus of the present invention secured in position on the housing of a rolling mill; Figure

2 is a front elevation of the apparatus; Figure 3 is a cross section therethrough 55 showing the elements of the apparatus in operative position; Figure 4 is a plan view of the apparatus; Figure 5 is a plan view of a modified form of the device which is adapted particularly for the bridling of 60 bars which are circular or rectangular in cross section; and Figure 6 is a front elevation of such modified form of the device.

The apparatus of the present invention comprises primarily side frame members or 65 arms 1 and 2, which are secured to the housing 3 of the rolling mill; stationary bridle bars 4 and 5 mounted in the side arms 1 and 2; and a movable member or bar 6 arranged to be swung between the stationary 70 bars across the plane of the axes thereof.

It is to be understood that the general object of bridling thin strips of metal passing to a rolling mill is to prevent buckling, curling, or warping of such strips. This object 75 may be effected by stationary bridle bars or by suitable automatic bridling apparatus which place the strip being rolled under tension, offering resistance against the pull 80 of the rolls. Some automatic means effect such bridling by wrapping the strip upon itself so that a frictional drag is produced between different portions of the same strip during passage of the strip to the reducing rolls of the mill. While this method of placing the strip under tension is satisfactory 85 when the strip is composed of certain metals, it is unsatisfactory if the strip is composed of certain other metals, and is notably so in the case of aluminum. 90

The device of the present invention deflects and grips a strip passing to the rolls without producing a frictional drag of the strip upon itself; of dragging the strip over any other metallic surface when such is 95 composed of aluminum.

As shown clearly in Figure 3 of the drawings, the strip 7 which is being rolled lies initially wholly on one side of both the stationary bars 4 and 5 in its passage to the 100 rolls, the strip being shown as lying above these bars. In order to deflect the strip, the movable member or bar 6 is provided. This movable member or bar 6 is carried by bracket arms 8, which are rigidly secured to 105 the trunnions 9 of stationary bar 4 inward-

ly of the side members 1 and 2 of the apparatus. It will thus be seen that the bar 6 revolves about a fixed axis, and that it describes the arc of a circle when swung.

5 In order to rotate bar 4, and swing movable bar 6, an operating handle 10 is rigidly secured to the outer extremity of the trunnion 9 which extends beyond the side frame member 1 of the apparatus. Movement of 19 the operating handle 10 serves to swing the bar 6 from the position shown in Figures 1 and 2 of the drawings into the position shown in Figure 3 thereof. The bar may be locked in either of these positions by 15 means of a spring pressed locking pin 11 which is arranged to enter notches 12 in a locking plate 13 secured to the side frame 2 of the apparatus.

20 As the bar 6 swings downward, describing the arc of a circle, it deflects the strip 7 downward with it and brings the strip into contact with a pair of contact rolls 14 which are rotatably mounted in bearing blocks 15 in the side members 1 and 2 of the apparatus. The strip 7 is thus gripped between the swinging bar 6 and the contact rolls 14 so that it is held under tension thereby and resistance to the pull of the reducing rolls.

25 30 If aluminum strips are being rolled the stationary bars 4 and 5, the swinging bar 6, and the contact bars or rolls 14 are all preferably provided with a fibre covering 16, so that the strip is not dragged in contact with 35 any metallic surface in its passage to the rolls of the rolling mill. The fibre or felt covers 16 on the bars may be omitted for the rolling of strips of brass, copper, steel, or in general any metal other than aluminum 40 or other metals the surfaces of which are subject to injury by being dragged over a metallic surface.

45 It will be observed that the length of the are described is limited, two definite positions only being provided for. For this reason it is necessary that the contact bars or 50 rolls 14 be vertically adjustable, in order that the strip may be gripped with the desired firmness, and in order that the apparatus may accommodate itself to strips of different thickness. For this purpose the bearing blocks 15 are slidably mounted for 55 limited vertical movement in the side members 1 and 2, and are provided with seats 17 for receiving a stiff flat spring 18. Against this flat spring 18 bears a screw threaded 60 plunger 19, which has a screw threaded engagement in a bracket 20 secured to the side members of the apparatus, and which is provided with an operating handle 21.

65 The bearing blocks 15 are provided with rounded lower faces which rest upon the flat spring 18 and provide the seat 17 therefor. Because of this, the bearing blocks 15 have a rocking mounting on the spring, and the

contact rolls or bars 14 are self adjusting so that they both bear equally at all times upon the strip 7 gripped between them and the bar 6, to exert an equal pressure thereon.

70 In use of the apparatus, the strip 7 is passed over the stationary bridle bars 4 and 5 and gripped by the rolls of the mill. The movable bar 6 is then swung across the plane of the axes of the stationary bridle bars into its lower position, and the contact rolls 14 75 are adjusted to grip the strip firmly and hold it under tension against the pull of the reducing rolls.

75 If a number of strips of uniform thickness are being rolled, a single adjustment of 80 the contact rolls serves throughout the bridling and rolling of all of such strips. In such case the only operations necessary in tensioning the strips consist in swinging the movable bar upwardly to permit a strip to 85 be led over the stationary bridle bars to the rolls of the rolling mill, and in swinging the movable bar downwardly to press the strip against the contact members.

85 The form of the apparatus illustrated in 90 Figures 5 and 6 of the drawings is adapted particularly for use in the bridling of bars of circular or rectangular cross section. For this purpose the apparatus shown in the preceding figures of the drawings may simply 95 be provided with bridle bars which have therein semi-circular or rectangular grooves for receiving a bar passing to the reducing rolls.

95 100 As shown in these figures of the drawings, however, the apparatus is contracted and comprises a spring 18^a and bracket 20^a shorter than the spring 18 and bracket 20, and bridle bars 4^a, 5^a, 6^a, and 14^a of lesser length than the corresponding bridle bars 105 designed for the bridling of flat bars, or strips. This is because bars of any great length are unnecessary for the purpose for which this form of the apparatus is intended. The shortened bars of this form of the 110 apparatus, as they are shown in Figure 5 of the drawings, are provided with rectangular grooves 22; while such bars, as they are shown in elevation in Figure 6 of the drawings, are provided with semi-circular 115 grooves 23.

115 With this form of the apparatus any covering for the bridling bars is omitted.

120 The device described is not only simple in construction and economical to manufacture, but also provides bridling means and operation of which is of extreme simplicity.

125 The advantages of the device as hereinabove set forth, together with numerous other advantages, will be readily appreciated by those skilled in the art to which the invention pertains.

130 As the device illustrated and described is, moreover, susceptible of a number of modifications without departing from the spirit

of the invention embodied therein, the scope of the invention is to be restricted only by the limitations contained in the claims appended hereto.

5. What I claim is:

1. In bridling apparatus for use in conjunction with rolling mills the combination of a plurality of stationary bridle bars, and a movable member pivotally mounted on one of said bars and arranged to be swung across the plane of the axes of said stationary bars.

2. In bridling apparatus for use in conjunction with rolling mills the combination of a plurality of stationary bridle bars, contact means disposed to one side of the plane of the axes of said bridle bars, and a pivotally mounted member arranged to be swung across said plane into proximity to said contact means.

3. In bridling apparatus for use in conjunction with rolling mills the combination of a plurality of stationary bridle bars, contact means disposed to one side of the plane of the axes of said bridle bars, and a member pivotally mounted on one of said bridle bars and arranged to be swung across said plane into proximity to said contact means.

4. In bridling apparatus for use in conjunction with rolling mills the combination of a plurality of stationary bridle bars, contact means disposed to one side of the plane of the axes of said bridle bars, and a member arranged to be moved across the plane of the axes of said bars into proximity to said contact means.

5. In bridling apparatus for use in conjunction with rolling mills the combination of a plurality of stationary bridle bars, contact rolls disposed to one side of the plane of the axes of said bridle bars, and a pivotally mounted member arranged to be swung across said plane into proximity to said contact rolls.

45. 6. In bridling apparatus for use in conjunction with rolling mills the combination of a plurality of stationary bridle bars, contact rolls disposed to one side of the plane of the axes of said bridle bars, and a member pivotally mounted on one of said bridle bars and arranged to be swung across said plane into proximity to said contact rolls.

55. 7. In bridling apparatus for use in conjunction with rolling mills the combination of a plurality of stationary bridle bars, contact rolls disposed to one side of the plane of the axes of said bridle bars, and a member arranged to be moved across the plane of the axes of said bridle bars into proximity to said contact rolls.

60. 8. In bridling apparatus for use in conjunction with rolling mills the combination of a plurality of stationary bridle bars, contact means disposed to one side of the plane of the axes of said bridle bars, a pivotally

mounted member arranged to be swung across said plane into proximity to said contact means, and means for locking said member in such position.

9. In bridling apparatus for use in conjunction with rolling mills the combination of a plurality of stationary bridle bars, contact means disposed to one side of the plane of the axes of said bridle bars, a member pivotally mounted on one of said bridle bars and arranged to be swung across said plane into proximity to said contact means, and means for locking said member in such position.

10. In bridling apparatus for use in conjunction with rolling mills the combination of a plurality of stationary bridle bars, contact means disposed to one side of the plane of the axes of said bridle bars, a member arranged to be moved across the plane of the axes of the bridle bars into proximity to said contact means, and means for locking said member in such position.

11. In bridling apparatus for use in conjunction with rolling mills the combination of a plurality of stationary bridle bars, contact rolls disposed to one side of the plane of the axes of said bridle bars, a pivotally mounted member arranged to be swung across said plane into proximity to said contact rolls, and means for locking said member in such position.

12. In bridling apparatus for use in conjunction with rolling mills the combination of a plurality of stationary bridle bars, contact rolls disposed to one side of the plane of the axes of said bridle bars, a member pivotally mounted on one of said bridle bars and arranged to be swung across said plane into proximity to said contact rolls, and means for locking said member in such position.

13. In bridling apparatus for use in conjunction with rolling mills the combination of a plurality of stationary bridle bars, contact rolls disposed to one side of the plane of the axes of said bridle bars, a member arranged to be moved across the plane of the axes of said bars into proximity to said contact rolls, and means for locking said member in such position.

14. In bridling apparatus for use in conjunction with rolling mills the combination of a plurality of stationary bridle bars, vertically adjustable contact means disposed to one side of the plane of the axes of said bridle bars, and a pivotally mounted member arranged to be swung across said plane into proximity to said contact means.

15. In bridling apparatus for use in conjunction with rolling mills the combination of a plurality of stationary bridle bars, vertically adjustable contact means disposed to one side of the plane of the axes of said bridle bars, and a member pivotally mounted on one of said bridle bars and ar-

1
ranged to be swung across said plane into proximity to said contact means.

16. In bridling apparatus for use in conjunction with rolling mills the combination of a plurality of stationary bridle bars, vertically adjustable contact means disposed to one side of the plane of the axes of said bridle bars, and a member arranged to be moved across the plane of the axes of said

bars and into proximity to said contact means.

In testimony whereof, we hereunto set our hands.

JOSEPH G. BAIN,
LASZLO M. STEMPPEL.
